United States Patent

Des. 241,386
Patented Sept. 14, 1976

241,386

MEDICAL CHAIR

Eric Alan Robin Lawrence, London, England, assignor to
Conebest Limited, Sussex, England

Filed Dec. 10, 1974, Ser. No. 531,281

Term of patent 14 years

Int. Cl. D6—01

U.S. Cl. D6—22

Fig.3.

Fig.4.

FIG. 1 is a side perspective view from the right side (looking forward) of a medical chair showing my new design;

FIG. 2 is a side perspective view of the medical chair from the other side thereof;

FIG. 3 is a front view of the medical chair; and

FIG. 4 is a rear view of the medical chair.

I claim:

The ornamental design for a medical chair, as shown.
